UNITED STATES PATENT OFFICE.

WILLIAM J. TETREAULT, OF PUTNAM, CONNECTICUT.

CAN-COVER FASTENER.

946,586.

Specification of Letters Patent.

Patented Jan. 18, 1910.

Application filed August 24, 1909. Serial No. 514,432.

To all whom it may concern:

Be it known that I, WILLIAM J. TETREAULT, a citizen of the United States, residing at Putnam, in the county of Windham and 5 State of Connecticut, have invented certain new and useful Improvements in Can-Cover Fasteners, of which the following is a specification, reference being had to the accompanying drawings.

10 My invention relates to improvements in fastening devices for the lids of milk cans and other receptacles or containers.

15 The object of the invention is to provide a simple and practical spring fastener of this character which will effectively secure the cover or lid of a can or the like.

20 With the above and other objects in view, the invention consists of the novel construction, combination and arrangement of parts, hereinafter fully described and claimed, and 25 illustrated in the accompanying drawings in which—

Figure 1 is a front elevation of a milk can having my improved fastener applied to its 25 cover. Fig. 2 is a vertical section taken on the plane indicated by the line 2—2 in Fig. 1. Fig. 3 is a horizontal section taken on the plane indicated by the line 3—3 in Fig. 1. Fig. 4 is a detail view of one of the jaws.

30 Referring more particularly to the drawings 1 denotes the neck or top of a milk can or similar receptacle or container. Said neck is provided with a surrounding reinforcing rib or flange 2 which forms a shoulder for engagement by the jaws 3 of my improved fastener. Said jaws are formed by the enlarged angularly bent outer ends of a pair of levers 4, the inner ends of which are pivotally united and arranged for sliding 35 movement in vertical guides between the cover or lid 5 of the can and the inverted U-shaped handle 6 of said cover. Said inner ends of the jaw levers 4 are notched to form tongues, which latter are bent upon themselves to provide alined hinge eyes 7 for the 40 reception of a pintle or pivot pin 8. Said pin 8 is preferably formed by the central portion of a wire loop 10, the ends of which latter project and slide in channeled upright 45 guides 11 between the cover and the top of the handle 6. The upper portion of the wire loop 10 is provided with an eye 12 formed by bending one end of said wire, and the other end of the latter is hooked into an 50 aperture 13 in one of the jaw levers 4. The eye 12 is engaged with the lower end of a

coil spring 14, the upper end of which is secured at 15 to the top of the handle 6 so that said spring tends to elevate the inner connected ends of the jaw levers and thereby draw the jaws 3 against opposite points of the shoulder or flange 2 to fasten the cover upon the can. The intermediate portions of the jaw levers 4 are guided in their sliding and swinging movement by guide loops 16 60 formed by the elongated eyes or eye bolts 17 passed through and secured in the cover 5, as shown in Fig. 2.

In operation, assuming the cover to be in position on the can, when it is desired to remove the cover the handle 6 is grasped with the thumb and first finger on the jaw levers 4, the latter are depressed thereby causing the jaws 3 to be swung outwardly out of engagement with the shoulder 2 to unlock 70 or unfasten the cover. By reversing this operation the cover may be quickly secured upon the can. It will be noted that when the cover is thus fastened it will be securely retained in position on the can so that it can 75 not come off should the can be overturned.

Having thus described the invention what is claimed is:

1. The combination of a container having external shoulders at its top, a cover for the 85 container, a pair of jaw levers having jaws at their outer ends to engage said shoulders, means on said cover for mounting the inner ends of said jaw levers for vertical sliding movement, and a spring for elevating the 90 inner ends of said jaw levers and maintaining their outer ends or jaws in engagement with said shoulders.

2. The combination of a container having external shoulders at its top, a cover for the 95 container, jaw levers having at their outer ends jaws for engagement with said shoulders, a handle on said cover, means on said cover for mounting the inner ends of said jaw levers for vertical movement and a coil 100 spring between the handle and said jaw levers for elevating the inner ends of the latter and maintaining their jaws in engagement with said shoulders.

3. The combination of a container having 105 external shoulders at its top, a cover for the container, a handle for the cover, upright guides, a pair of jaw levers having alined hinge eyes at their inner ends and jaws at their outer ends for engagement with said shoulders, a wire loop arranged in said hinge eyes to pivotally connect the jaw 110

levers, the projecting ends of said loop being
slidable in said guides, one end of the wire
forming said loop being bent to provide an
eye and the other end being anchored in one
5 of said jaw levers, guides on the cover for
the intermediate portions of the jaw levers
and a coil spring having its upper end con-
nected to said handle and its lower end en-
gaged with said eye.

10 4. The combination of a container having
external shoulders at its top, a cover for the
container, a handle for the cover, upright
guides, a pivot vertically slidable in said

guides, a pair of jaw levers to swing from
said pivot and provided at their outer ends 15
to engage said shoulders on opposite points
of the container, guides upon the cover for
the intermediate portions of the levers, and
a spring for elevating the pivoted inner ends
of said levers.

20 In testimony whereof I hereunto affix my
signature in the presence of two witnesses.

WILLIAM J. TETREAULT.
